SLINGSHOT OR SIMILAR ARTICLE

William H. H. Griffin, Seymour, Tex.

Application April 10, 1952, Serial No. 19,273

Term of patent 14 years

(Cl. D34—15)

To all whom it may concern:

Be it known that I, William H. H. Griffin, a citizen of the United States, residing at Seymour, Baylor County, Texas, have invented a new, original, and ornamental Design for a Slingshot or Similar Article, of which the following is a specification, reference being had to the accompanying drawing, forming a part hereof.

Figure 1 is a front perspective view of a slingshot or similar article embodying my new design; Figure 2 is a front elevational view of the stock; Figure 3 is a rear elevational view thereof, and Figure 4 is a top plan view of the stock.

The essential features of my design are shown in full lines.

I claim:

The ornamental design for a slingshot or similar article, substantially as shown and described.

WILLIAM H. H. GRIFFIN.
